SAFETY RAZOR

Joseph Muros, Cambridge, Mass., assignor to Gillette Safety Razor Company, Boston, Mass., a corporation of Delaware

Application January 21, 1944, Serial No. 519,213

8 Claims. (Cl. 30—65)

This invention relates to safety razors of the type in which a thin flexible blade is shaped and supported for shaving between blade-clamping members. The invention consists in improvements facilitating the presentation to the razor of fresh sharp blades while each blade is protected by an envelope or cover which it is desired to remove only after the blade has been positively located in its shaving position.

The shaving edge of a thin safety razor blade is brought to such a high degree of fineness that it is extremely delicate and its keenness is likely to be destroyed if the edge is accidentally drawn across any part of the razor or a blade magazine or even the blade wrapper preparatory to shaving. Great care and considerable skill is required ordinarily on the part of the user to extract such a sharp blade from its wrapper and present it safely in its shaving position without damage to its edge. The present invention deals with blades of a type which may be protected at the time or place of manufacture by being enclosed in a paper cover or wrapper. This wrapper overlaps and safeguards the sharp edge or edges of the razor blade and must be removed to make the edge accessible for shaving. We contemplate a safety razor so organized that the wrapped blade may be delivered directly thereto in its final shaving position and temporarily held as thus positioned while the user has only to strip the wrapper from the blade and withdraw it from the razor, all this being effected without danger and even without the possibility of touching the keen cutting edge of the blade.

An object of the invention is to provide a compact structure without moving parts which may conveniently be embodied in safety razors of well-known commercial types for effecting these desirable results. To this end a feature of the invention comprises a detent or retainer on one of the blade-clamping members having an inclined face arranged to meet the on-coming end of a flexible blade and ride up upon it under spring pressure as the blade is inserted. When the blade has once been moved fully into its shaving position it automatically springs into a flat condition and simultaneously the detent engages an aperture provided for that purpose in the blade. With the blade thus held the user has only to strip the protective cover by pulling it endwise whereupon the blade may be clamped in final position for shaving, either flat or in a condition of transverse curvature depending upon the type of razor in which the invention is embodied.

An important feature of the invention consists

in a detent fixed to one of the blade-clamping members and having an inclined blade-engaging surface so disposed in the razor that the blade-clamping members are temporarily separated by a prying action of the detent in cooperation with the blade until the blade has been advanced to a position registering with the detent. When this position is arrived at the blade settles itself quickly upon the detent with the elimination of all the preliminary distorting strains which have accompanied the insertion of the blade in the razor.

These and other features of the invention will be best understood and appreciated from the following description of a preferred embodiment thereof, selected for purposes of illustration and shown in the accompanying drawing, in which:

Fig. 1 is a view in perspective of the complete razor showing a blade being inserted with its protective cover in place;

Fig. 2 is a corresponding view in longitudinal section and on an enlarged scale;

Fig. 3 is a view in perspective of the cap as seen from beneath; and

Fig. 4 is a plan view of a blade in position on the cap member of the razor.

The razor herein shown is designed to employ interchangeable blades of the type best shown in Fig. 4. The blade 10 is generally rectangular in outline having corner recesses which define elongated unsharpened end portions and is sharpened at both longitudinal edges. It is a blade of the open-ended type, that is to say, it has a central longitudinal slot 11 opening through one end of the blade, the other end being solid. The slot 11 widens out in its length into a pair of square enlargements 12 and into a circular central aperture 13. The blade is protected by a paper, fiber or foil cover 14 folded lengthwise over the shoulders at the left-hand end of the blade as seen in Fig. 1 and having tabs which are folded inwardly over the cover at the right-hand end of the blade. The cover is folded so that the sharp edges of the blade do not contact the material of the cover.

The razor herein shown includes in its structure a handle, guard and cap. The cap 16 is rectangular in outline and slightly narrower than the blade. It has an inner concave blade-engaging face from which projects a central blade-locating rib 17. The rib 17 is of uniform height or depth except in a limited section 15 at each end which is higher or deeper than the body of the rib. Near one end of the rib 17 is provided a stationary detent or lug consisting of two simi-

lar sections 18, one located on each side of the rib and together being considerably thicker than a rib in overall width. The detent sections 18 have downwardly and rearwardly sloping blade-engaging faces at either side of the rib 17. The overall dimensions of the detent or lug and the rib 17 corresponds to the width of the aperture 12 in the blade. The rib merges centrally into a downwardly extending stem 19. The two rear-most corners of the cap are provided with corner lugs 20 which fit with clearance into corresponding notches of the blade as shown in Fig. 4. The other end of the cap is cut away centrally to provide a wide shallow finger recess 21 for convenience in presenting and removing a blade from the razor.

The guard 25 corresponds in outline to the cap except that it is substantially wider and it is provided with a convex blade-supporting face which, when a blade is fully clamped in shaving position, cooperates with the cap in imparting transverse curvature thereto. The guard is provided with a longitudinal recess 26 to receive the blade-locating rib 17 of the cap and is connected rigidly to the upper end of the handle 27. At either end of the recess 26 is provided a short slot 24 shaped to receive with a sliding fit the higher end sections 15 of the rib 17.

The handle 27 is bored to receive the stem 19 of the cap and chambered to receive a compression spring 28 which bears at its lower end against the inner end of a cylindrical nut 29 having threaded engagement with the lower end of the spindle 19. A stop screw 30 in the lower end of the spindle prevents by its head accidental disengagement of the parts. The nut 29 is shouldered as shown to bear against the end of the barrel 27 so that by turning the nut 29 in a clockwise direction the stem 19 may be drawn positively downwardly within the barrel and a positive clamping pressure created between the cap and guard. On the other hand, when the nut 29 is rotated reversely clearance is provided under the head of the screw 30 and the spindle 19 may then be elevated against the compression of the spring 28 so as to separate the cap from the guard temporarily and thus permit interchange of blades. To cause such separation the user may hold stationary the upper portion 27 of the handle and push-up on the tubular nut 30, as suggested in Fig. 2. The spring 28 tends at all times to move the cap and guard toward each other.

In Fig. 2 the user is represented as having slightly separated the cap and guard against the action of the spring 28 by the act of inserting the projected blade from the right-hand end of the razor. The open end of the blade is presented in advance, the side portions of the blade passing on each side of the rib 17. When the side portions of the blade reach the inclined faces of the detent 18 they react against the detent to separate the cap still further from the guard as shown in Fig. 2. This prying action continues as the blade is advanced until the slot enlargement or aperture 12 of the blade registers with the detent sections 18. When this occurs the resiliency of the blade snaps it into substantially flat condition with the detent 18 passing freely through the enlargement 12. The blade is thus anchored against longitudinal movement in the razor and, while it is so held, the user may strip the cover 14 by merely pulling it to the right off the blade. The bare blade now lies safely

within the razor and fully in its shaving position as suggested in Fig. 4. Its sharp edges have not touched or been touched by any object and so retain their initial keenness. Complete and final clamping of the blade for shaving is in no way interfered with and when the user has rotated the nut 29 to clamp the blade in its position he may proceed with the shaving operation.

As already noted, the spring 28 tends at all times to move the cap and guard together in a yielding manner. The cap may be lifted by the wedging action of a blade riding up upon the inclined end faces of the detent sections 18, or the user may lift it by pressing upwardly on the nut 29 when the latter has been unscrewed on the stem 19 enough to afford clearance. When it is desired to remove a used blade the user must lift the cap in this manner sufficiently to free the detent from the square slot enlargement 12. The blade may then be withdrawn for cleaning or replacement.

In all positions of the cap and guard, including the position of their maximum separation as determined by the screw 30, the higher sections 15 of the rib of the cap play in the slots 24 of the guard, with the result that the proper alignment of the razor elements is always maintained.

While the corner lugs 20 of the cap do not ordinarily engage the blade 10 at any time, they do serve as a safeguard to limit the spreading that might otherwise occur as a result of pulling the blade against the detent in removing its protective cover. The clearance between the lugs 20 and the end of the blade 10 is always less than the width of the sections of the detent 18 on each side of the rib 17. Therefore, the side portions of the blade can never spread sufficiently to slip past the detent in the operation of removing the blade cover.

This application is a continuation-in-part of my application, Serial No. 497,572, filed August 6, 1943.

Having thus disclosed by invention and described one illustrative embodiment thereof, I claim as new and desire to secure by Letters Patent:

1. A safety razor having cooperating blade-clamping members, blade-locating means on one of said blade-clamping members, and a detent located on and immovable with respect to the same member and shaped for engagement by a flexible apertured blade when the latter is presented endwise between the clamping members, said detent contacting the surface of the blade until its aperture has been advanced to register with the detent and then entering the aperture and holding the blade against withdrawal.

2. A safety razor having cooperating blade-clamping members, a blade-locating rib extending from one toward the other, and a detent fixed to one of the blade-clamping members near one end of the rib with an inclined blade-engaging face where it may first contact the surface and then enter a flexible apertured blade presented endwise between said blade-clamping members.

3. A safety razor having cooperating blade-clamping members one of which has a longitudinal rib projecting toward the other, and a detent located with sections on each side of said rib and having a bevelled end surface below the top of the rib.

4. A safety razor having cooperating blade-clamping members, a spring tending at all times

to move them together, and an interposed detent on one member near one end of said members having a bevelled face for engaging the end of an on-coming blade pushed endwise between said members and temporarily separating them by a cooperating prying action of the blade and detent.

5. A safety razor having cap and guard members, a blade-locating rib on the cap and a fixed detent near one end of the rib having an oblique to end face, a spring pressing said members together, a blade with an open-ended longitudinal slot fitting said rib and having an enlargement near one end fitting said detent, and means for 10 temporarily separating said members in opposition to the action of said spring for the removal of a blade.

6. A safety razor having cooperating blade-shaping members, a straight blade-locating rib projecting from one of said members, a detent 15 of less height than said rib located between the ends of the rib and having a top face inclined with respect to the edge of the rib, whereby an open end blade pushed endwise along the rib may be displaced by wedging action and thus sep-

20 arate the said blade-shaping members, and a spring urging said members together in opposition to such wedging action.

7. A safety razor having cooperating blade-clamping members, a blade-locating rib extending from one member toward the other, a detent fixed upon said rib, having a blade-engaging face and being shaped to enter an aperture in a flexible open-end blade presented endwise between said blade-clamping members, and spaced lugs on one of said members limiting possible spreading of the blade to an amount less than the width of said detent.

8. A safety razor having a guard, and a cap with a blade-locating rib and a fixed detent wider than the rib, in combination with an open-end, apertured blade having sharpened side portions separated by a medial slot and being fitted upon said rib and detent, and spaced lugs on the cap normally clearing the ends of the blade and located to prevent spreading of the side portion of the blade sufficiently to release the blade from said detent.
